United States Patent

Des. 234,551
Patented Mar. 25, 1975

234,551

ATTACHING APPARATUS OR SIMILAR ARTICLE

Gregory F. Fossella, Marshfield, and Lawrence R. Hoffman, Burlington, Mass., assignors to Dennison Manufacturing Company, Framingham, Mass.

Filed June 22, 1973, Ser. No. 372,820

Term of patent 14 years

Int. Cl. D8—05

U.S. Cl. D3—19 A

FIG. 1

FIG. 3

FIG. 2

FIG. 5

FIG. 4

FIG. 1 is a top view of an attaching apparatus showing our new design;

FIGS. 2 and 4 are side views of said attaching apparatus of FIG. 1;

FIG. 3 is a front view of the attaching apparatus of FIG. 1; and

FIG. 5 is a rear view of said attaching apparatus or similar article showing our new design.

We claim:

The ornamental design for an attaching apparatus or similar article, substantially as shown and described.
